(57) **CLAIM**

The ornamental design for a ventilated batter's helmet, as shown and described.

DESCRIPTION

FIG. 1 is a perspective view of the ventilated batter's helmet in accordance with the design of the present invention;

FIG. 2 is a top plan view of the ventilated batter's helmet of FIG. 1;

FIG. 3 is a bottom plan view of the ventilated batter's helmet of FIG. 1;

FIG. 4 is an elevational view from one side of the ventilated batter's helmet of FIG. 1;

FIG. 5 is an elevational view from the other side of the ventilated batter's helmet of FIG. 1;

FIG. 6 is a front end elevational view of the ventilated batter's helmet of FIG. 1; and,

FIG. 7 is a rear end elevational view of the ventilated batter's helmet of FIG. 1.

The details shown in broken lines are for illustrative purposes only and form no part of the claimed design.
